THOMAS J. HOLLAND, OF AMSTERDAM, NEW YORK, ASSIGNOR TO BIGELOW-SANFORD CARPET CO., INC., OF THOMPSONVILLE, CONNECTICUT, A CORPORATION OF MASSACHUSETTS

TUFT FILE FABRIC LOOM

Application filed April 8, 1932. Serial No. 604,018.

This invention relates to looms for weaving tuft pile fabrics, and more particularly tuft pile fabrics wherein the pattern of the pile surface is reproduced upon the back.

5 Tuft pile fabrics, such, for instance as Axminster and like carpets and rugs, as ordinarily woven present an objectionable looseness of the backing fabric and of the pile forming tufts where they pass about 10 the tuft holding weft shot, due to the fact that the binding weft shot is beaten up under conditions which fail to draw the tufts tightly about the holding weft shot with the result that the pile forming tufts work 15 loose and become detached from the ground fabric, and the pattern on the back, as well as the pile surface, presents a distorted and unsatisfactory appearance.

The ordinary Axminster loom is provided 20 with a fixed breast plate over which the fabric passes as it is woven and loops of the tuft yarn which may pass about a back weft shot are supported upon the surface of the breast plate near its rear edge. On the beat 25 up of the lay the reed approaches the rear edge of the breast plate but terminates its beat-up action short of the rear edge of the breast plate with the result that the binding weft shot for the pile forming tufts is not 30 driven into close binding relation with the tufts and the fabric presents a loose weave with the objections above noted.

One of the objects of the present invention is to produce a tuft pile fabric of the Ax- 35 minster or similar type wherein the objections heretofore existing may be eliminated, the pile forming tufts be drawn tightly about the holding weft shot, and a well defined pattern of the pile surface be pro- 40 duced upon the back of the finished fabric.

In accordance with the present invention the breast plate is moved rearwardly at intervals and is returned to its front position by a part carried by the lay on the beat up 45 of the binding weft shot for the pile forming tufts, the effect being that on its rearward movement the back legs of the pile forming tufts are turned upwardly, the loops of the tufts are supported by the 50 breast plate, and while so supported the ad-

vancing lay beats up the binding weft shot for the tufts and returns the breast plate to front position, thus drawing the tufts tightly about the holding back shot and producing a close weave of the ground fabric with a clear and well defined pattern on the back. 55

The invention and novel features thereof will best be made clear from the following 60 description and accompanying drawings of one good practical form or embodiment thereof. 65

In the drawings:—

Fig. 1 is a sectional side elevation of a 65 tuft pile fabric loom containing the present invention;

Fig. 2 is a fore and aft section on an enlarged scale showing the movable breast plate being moved to its rearward position, 70 the lay and reed being shown in elevation;

Fig. 3 is a view similar to that of Fig. 2 showing the relation of parts as the breast plate is being moved forwardly;

Fig. 4 is a view of the breast plate extending transversely of the loom; and 75

Fig. 5 is a perspective broken out detail of the breast plate and its associated parts.

The invention will be described in connection with a loom of the well known Axminster type and as indicated in Fig. 1 the loom frame 1 may be of usual construction and at the rear portion thereof supports the warp beams 2 and 3 from which the warp threads pass forwardly through the usual weaving 80 mechanisms. 85

Rising from the loom frame 1 are the standards 4 having brackets 5 for the support of the usual sprockets 6 about which the tube frame carrier or chains pass. The 90 carrier or chains 7 support a number of tube frames, 8 as usual in the Axminster loom and such tube frames carry the pile forming tuft yarns. The tube frames 8 are taken from the carrier or chains 7 by a 95 transerrer 9 to present the pile forming tuft yarns to the weaving point.

As indicated in Fig. 1 the cutter carriers 10 and 11 have the usual cutters for parting 100 or cutting the pile forming tufts after the

latter have been introduced about the holding weft shot at the weaving point.

Mounted upon the shaft 12 is the lay 13 having a reed 14 and the lay is given its movements towards and from the front of the loom by a rod or connection 15 actuated by a going part of the loom.

The comb 16 is given its appropriate movements as usual to turn up the rear legs of the tuft yarns and then recede by means of actuating connections 17 and 18. As the fabric is woven it passes frontwardly about the spike roll 19.

All of the parts so far described may be of usual construction now well known to those familiar with Axminster or tuft pile fabric looms and further elucidation of these features is unnecessary.

Mounted upon the front portion of the loom is the breast beam 20 which forms a convenient support for the movable breast plate 21 which is mounted on the breast beam for movements rearwardly and frontwardly.

In accordance with the present invention the breast plate 21 is to be moved rearwardly at intervals and then freed from the moving means that it may be returned frontwardly on the beat-up by means carried on the lay.

In the present instance of the invention the breast beam 20 and the movable breast plate 21 are associated for sliding movement of the latter rearwardly and frontwardly and while various means may be devised for effecting the relative movement of the breast plate and the breast beam, in the present instance the breast plate 21 is connected to the breast beam 20 at each end of the breast plate by bolts or screws 22 which pass through elongated slots 23 in the breast plate with the result that the breast plate may be moved backwardly and frontwardly relative to the breast beam and in order that the breast plate may be supported and guided at intervals the breast beam has secured thereto the supporting lugs 24 which extend beneath the breast plate, and, as indicated in Fig. 4, two or more of such supporting lugs may be utilized.

It is likewise desirable that the breast plate may be held from displacement vertically and to this end the breast beam 21 has secured thereto the guides 25 of which there may be an appropriate number to effect the purpose. From the construction thus far described it will be apparent that the breast plate 21 is mounted for movement on the breast beam in a direction backwardly and frontwardly.

As more clearly indicated in Figs. 2 and 3 the guides 25 are connected to the breast beam by screws 26 and the rearwardly projecting end portions of the guides 25 overlie

portions of the breast plate. In the present instance of the invention the upper surface of the breast plate 21 adjacent the guides 25 is provided with a recess 27, and a recess 28 is preferably formed at the gooseneck portion of the guides 25 to permit the breast plate a limited but substantial movement backwardly and frontwardly.

The breast plate 21 is provided with a rib or projection 29 extending longitudinally thereof and formed with openings at intervals for the rearwardly extending portion of the supporting lugs 24, the construction being such that while the lugs 24 support the breast plate they do not interfere with the movement of the breast plate backwardly and frontwardly.

Secured to the rib or projection 29 of the breast plate at intervals are the arms 30 which afford means for engagement with an actuating member or members for moving the breast plate rearwardly. In the present instance the arms 30 are provided with pins 31 which enter elongated recesses 32 formed in the upper portion of the actuating members 33.

The function of the actuating members 33 is to move the breast plate rearwardly at intervals and then free the breast plate for movement frontwardly by a part carried on the lay on the beat up of the binding weft shot for the tufts, and since the actuating members are similar a description of one will be sufficient. Referring to Fig. 1 the actuating member 33 is mounted for rocking movement on a transversely extending shaft 34 which may be carried in bearings 35 secured to the front girth 36 of the loom.

Connected to the actuating member 33 is a rod 37 which if desired may be provided with a turn buckle 38 for adjustment purposes and the rear end portion of the rod 37 is connected at 39 to a lever 40 mounted for rocking movement on a support 41 carried by suitable brackets 42 secured to the rear girth 43 of the loom.

The lever 40 is provided with a roller 44 and under the impulse of a spring 45 secured at one end to the upper portion of the lever 40 and at its other end to a fixed portion 46 the roller 44 is held in contact with a surface of a cam disk 47 which is mounted upon the cam shaft 48 actuated by a going part of the machine.

The cam disk 47 carries a cam 49 which, as it passes under the roller 44 gives the actuator 33 a movement to carry the breast plate 21 rearwardly, and then free the breast plate that it may rest in its rearward position and be held there by the frictional engagement of the breast plate with its guiding means.

From the construction thus far described it will be apparent that the actuating member 33 moves the breast plate to a rearward

position under the impulse of the cam 49 and then immediately the actuating member moves back to its normal position, as indicated by dotted lines in Fig. 2, thus freeing 5 the breast plate in the rearward position to which it has been moved.

It may be desirable at times to adjust the rearward position of the breast plate or vary its position for reasons that will later appear 10 and consequently the actuating member 33 is provided with a lug 50 in which is threaded an adjusting member or screw 51 whereby the effective length of the slot 32 of the actuating member 33 may be varied and consequently 15 the rear position to which the breast plate is moved may be changed.

In the particular construction of the tuft pile fabric selected for illustration of the invention and its operation there is a surface 20 weft shot *a*, a tuft holding weft shot *b* and a binding weft shot *c* but obviously the number of weft shots will be varied in accordance with the construction of the fabric to be woven.

25 During the insertion of the surface weft shot *a* and the holding weft shot *b* about which the tuft yarns *d* are passed the breast plate 21 is in its front position. Upon the insertion of the binding weft shot *c* for the 30 tuft yarns, the breast plate is moved rearwardly, as indicated in Fig. 2, thereby turning the rear leg of the tuft yarns upwardly and supporting the loops thereof, and at this time also the comb 16 is actuated to complete 35 the upturning movement of the tuft yarns. As the binding weft shot *c* is beaten up the reed 14 engages the rear edge portion of the breast plate 21 and moves the breast plate forwardly thereby causing the binding 40 weft shot *c* to draw the loop of the tuft yarns tightly about the holding weft shot *b*, as indicated in Fig. 3.

The result of the general operation described is to tighten the loops of the tufts 45 about the holding weft shot to make a close weave and securely anchor the tuft yarns in the backing fabric with the production of a well defined pattern on the back of the completed fabric.

50 What is claimed is:—

1. In a loom for weaving tuft pile fabrics, the combination of a breast plate, means for moving the breast plate rearwardly to support the loops of the pile forming tufts 55 about the holding weft shot and freeing the breast plate in its rearward position, the lay having movements towards and from the front of the loom, and means carried by the lay for moving the breast plate forwardly on the beat up.

2. In a loom for weaving tuft pile fabrics, the combination of a breast plate mounted for sliding movement, means for sliding the breast plate rearwardly at intervals to support the loops of the pile forming tufts about

the holding weft shot and freeing the breast plate in its rearward position, the lay having movements towards and from the front of the loom, and means carried by the lay for sliding the breast plate frontwardly on the beat up of the binding weft shot for the pile forming tufts. 70

3. In a loom for weaving tuft pile fabrics, the combination of a breast plate mounted for movement towards and from the front of the loom, means for moving the breast plate rearwardly at intervals and freeing the breast plate in its rearward position that the loops of the pile forming tufts may be supported about the holding weft shot, the lay for beating up the weft shots, and means actuated by lay movement for engaging and moving the breast plate frontwardly from its rearward position on the beat up of the binding weft shot for the pile forming tufts. 80

4. In a loom for weaving tuft pile fabrics, the combination of a sliding breast plate, means for sliding the breast plate rearwardly at intervals and freeing the breast plate in its rearward position, the lay and reed having movements towards and from the front of the loom and engageable with a part of the breast plate when it is in its rearward position to effect movement of the breast plate frontwardly and cause the binding weft shot to draw the loops of the pile forming tufts tight about the holding weft shot. 90

5. In a loom for weaving tuft pile fabrics, the combination of a sliding breast plate, means for sliding the breast plate rearwardly at intervals and freeing the breast plate in its rearward position, devices for varying the position to which the breast plate is moved by said means, the lay and reed having movements towards and from the front of the loom and engageable with a part of the breast plate when it is in its rearward position to effect movement of the breast plate frontwardly and cause the binding weft shot to draw the loops of the pile forming tufts tight about the holding weft shot. 100

6. In a loom for weaving tuft pile fabrics, the combination of the breast beam, a breast plate mounted on the breast beam for movement toward and from the front of the loom, an arm having a lost motion connection with the breast plate for moving the latter rearwardly to a predetermined position and freeing it for independent movement frontwardly, the lay having a reed and mounted for movement towards and from the front of the loom to beat up the weft shots and to engage the rear portion of the breast plate when in its rearward position and move it frontwardly on the beat up of the binding weft shot for the pile forming tufts to form a well defined pattern of the pile surface on the back. 110

7. In a loom for weaving tuft pile fabrics, 120

the combination of the breast beam, a breast plate mounted on the breast beam for movement towards and from the front of the loom, an arm having a lost motion connection with the breast plate for moving the latter rearwardly to a predetermined position and freeing it for independent movement frontwardly, friction means for holding the breast plate in its rearward position, 5 the lay having a reed and mounted for movement towards and from the front of the loom to beat up the weft shots and to engage the rear portion of the breast plate when in its rearward position and move it 10 forwardly on the beat up of the binding weft shot for the pile forming tufts to form a well defined pattern of the pile surface on the back.

8. In a loom for weaving tuft pile fabrics, 20 the combination of a breast beam, a breast plate mounted on the breast beam for movement towards and from the front of the loom, an operating arm, a pin and elongated slot connection between the breast plate and 25 operating arm for moving the breast plate to a rearward position to support the loops of the pile forming tufts and freeing the breast plate for movement frontwardly independent of the operating arm, and the lay 30 having a reed for engaging the breast plate when in its rearward position and acting to move the breast plate frontwardly on the beat up.

9. In a loom for weaving tuft pile fabrics, 35 the combination of a breast plate mounted for movement towards and from the front of the loom, means for moving the breast plate rearwardly at intervals and freeing the breast plate in its rearward position, and independent means actuated by 40 lay movement for moving the breast plate frontwardly.

10. In a loom for weaving tuft pile fabrics, the combination of a breast plate 45 mounted for movement towards and from the front of the loom, means for moving the breast plate to a rearward position at intervals, devices for varying the position to which the breast plate is moved by said 50 means, and independent means actuated by lay movement for moving the breast plate frontwardly.

11. In a loom for weaving tuft pile fabrics, the combination of a movable breast 55 plate guides for directing the movements of the breast plate towards and from the front of the loom, an operating arm for moving the breast plate rearwardly, a lug connected 60 to the breast plate, a pin and elongated slot connection between the lug and operating arm, means for adjusting the connection between the pin and elongated slot for varying the position to which the breast plate 65 may be moved by the operating arm, and

means independent of the operating arm for moving the breast plate frontwardly.

12. In a loom for weaving tuft pile fabrics, the combination of a breast plate mounted for movement towards and from 70 the front of the loom, means for moving the breast plate rearwardly at intervals to turn the rear leg of the pile forming tufts upwardly and support the loops of the pile forming tufts and freeing the breast plate 75 in its rearward position, and means carried by the lay for moving the breast plate frontwardly on the beat up of the binding weft shot for the pile forming tufts.

In testimony whereof, I have signed my 80 name to this specification.

THOMAS J. HOLLAND.
